UNITED STATES PATENT OFFICE

WILLIAM E. TRUMPLER, OF EASTON, PENNSYLVANIA, ASSIGNOR TO INGEBSOLL-RAND COMPANY, OF JERSEY CITY, NEW JERSEY, A CORPORATION OF NEW JERSEY

CENTRIFUGAL BLOWER

Application filed May 8, 1931. Serial No. 535,838.

This invention relates to multi-stage centrifugal blowers, compressors and the like, and more particularly to a diaphragm interposed between stages of apparatus of this character.

One object of the invention is to avoid undue acceleration and consequent pressure loss between stages.

Another object is to assure a comparatively direct path of flow for the fluid from a diffuser chamber into the guideways leading to the eye of a succeeding stage impeller.

Other objects will be in part obvious and in part pointed out hereinafter.

15 In the drawings accompanying this specification and forming a part thereof,

Figure 1 is a sectional elevation of a portion of a centrifugal blower equipped with a diaphragm constructed in accordance with the practice of the invention,

Figure 2 is a transverse view taken through Figure 1 on the line 2—2 looking in the direction indicated by the arrows, and

25 Figure 3 is a top plan view of the diaphragm.

Referring more particularly to the drawings, the blower which is designated generally by A comprises a casing B consisting of

casing A is of larger diameter than the impellers K and L and the impellers are suitably spaced along the length of the shaft J to permit the arrangement between adjacent impellers of diaphragms O which are so spaced with respect to each other as to form therebetween diffuser chambers P into which the fluid pumped by the impellers is discharged.

Each diaphragm O constructed in accordance with the practice of the invention may consist of upper and lower half-sections Q and R respectively. The sections Q and R may be identical in all their essential respects and comprise outer and inner walls S and T which are connected together by vanes U, shown in this instance as being of involute shape to form correspondingly shaped guideways V through which the fluid flows from the diffuser chamber P to the eye W of a succeeding stage impeller.

In order that the fluid may flow from the diffuser chamber P into the adjacent guideways V along a path of minimum tortuosity the wall S is provided with suitable notches or recesses X which are defined by a portion Y of the peripheral surfaces of the vanes U and by stepped portions Z of the wall S which

ing its course from the diffuser chamber P into the guideway V.

By directing the fluid along the course described, an efficient conversion of velocity into pressure may be effected in the guideways V. This is an extremely desirable feature and may probably be more fully appreciated by comparing the present structure with diaphragms as heretofore constructed and in 10 which a pair of circular walls of different diameter are held in spaced relation by vanes disposed therebetween to form guideways through which the fluid flows from the diffuser chamber to a succeeding stage impeller.

In blowers as at present constructed, however, the wall of smaller diameter and which would therefore correspond to the wall S of the present structure, being circular and extending with its periphery to at least the outer ends of the vanes, requires that the pressure fluid make an abrupt or right-angle turn to pass thereover to the inlet opening of the guideways and therefore a second 20 right-angle turn in entering the guideways. The fluid must, in view of this arrangement, follow an extremely tortuous path from the diffuser chambers into the guideways with consequent undesirable acceleration and 30 considerable pressure loss. This is of course highly objectionable in apparatus of this character and in which, unlike compressors of the reciprocatory type, the pressure of the fluid is not increased by very substantial values in individual stages.

As is of course well known, owing to the work of compression the temperature of the fluid increases progressively during its passage through the several stages of the blower.

40 In other words, the temperature of the fluid flowing through the diffuser chamber P associated with the impeller K and which, for this purpose, may be considered as being the first stage impeller, is increased considerably 45 above atmospheric temperature, and the temperature is again increased during the passages of the fluid through the impeller L and its diffuser chamber P.

Unless effectively restrained the heat of 50 the fluid of higher value will be transmitted to adjacent guideways and diffuser chambers and be absorbed by the fluid flowing therethrough, thus causing a reduction in the efficiency of the blower.

55 In view of the foregoing facts it is contemplated to insulate the guideways V from the diffuser chamber P of a succeeding stage. To this end the diaphragm O is provided with an additional wall e to form a bounding surface 60 for the diffuser chamber P associated with the succeeding stage impeller, as for instance the impeller L. The wall e, which is connected at its ends with the wall T, is suitably spaced with respect to the wall T to form 65 therebetween an annular insulating chamber

f which may be either an air pocket or, as shown, may be used as a water jacket to effect an additional cooling of the fluid flowing over the walls T and e.

In order to render the space f capable for 70 use as a water jacket the diaphragm is provided in its periphery with a port g through which water may be introduced into the chamber f. Such water may be conveyed to the chamber f by a connection h threaded 75 into the casing A and communicating with a groove j in the periphery of the diaphragm O.

Preferably the diaphragm O is provided on its periphery with a pair of ribs k which are located on opposite sides of the groove j and extend into an internal groove o in the casing A to conveniently maintain the diaphragm O in the proper position relatively to the impellers K and L, and also to effect a suitable fluid tight joint at this point between 80 adjacent diffuser chambers.

In practice, the present invention has been found to be extremely efficient. By means of the arrangement described a comparatively direct path has been provided for the fluid from the diffuser chamber P into the guideways V. No portion of the path followed by the fluid from the diffuser chamber to a succeeding stage impeller is restricted and, as a result thereof, the conversion of the velocity of the fluid into pressure may be efficiently brought about. Moreover, by insulating the guideways V from the comparatively high temperature prevailing in the diffuser chamber of a succeeding stage, the temperature of the fluid flowing through the guideways is in no wise increase above the value contained upon the discharge of the fluid from the immediately preceding stage 95 impeller.

I claim:

1. A multi-stage centrifugal blower including a plurality of impellers, diffuser chambers to receive the fluid from the impellers, a diaphragm between adjacent impellers, vanes on the diaphragm forming guideways to convey fluid from a diffuser chamber to a succeeding stage impeller, and a wall forming a closure for one side of the guideways and having notches through which fluid flows to the inlet openings of the guideways.

2. A multi-stage centrifugal blower including a plurality of impellers, diffuser chambers to receive the fluid from the impellers, a diaphragm between adjacent impellers, vanes on the diaphragm forming guideways to convey fluid from a diffuser chamber to a succeeding stage impeller, and a wall forming a closure for one side of the guideways and having portions of its periphery coincident with portions of the outer surfaces of the vanes, said wall having stepped portions extending from the outer ends of the 110 115 120 125 130

vanes to intermediate portions of adjacent vanes.

3. A multi-stage centrifugal blower including a plurality of impellers, diffuser chambers to receive the fluid from the impellers, a diaphragm between adjacent impellers, vanes on the diaphragm forming guideways to convey fluid from a diffuser chamber to a succeeding stage impeller, and

10 a wall forming a closure for one side of the guideways and having recesses therein to enable fluid to flow over intermediate portions of the vanes to the inlet openings of adjacent guideways.

15 4. A multi-stage centrifugal blower including a plurality of impellers, diffuser chambers to receive the fluid from the impellers, a diaphragm between adjacent impellers, vanes on the diaphragm forming

20 guideways to convey fluid from a diffuser chamber to a succeeding stage impeller, a wall forming a closure for one side of the guideways and having recesses therein to enable fluid to flow over intermediate portions

25 of the vanes to the inlet openings of adjacent guideways, and means on the diaphragm to form an insulating chamber between the guideways and a diffuser chamber.

In testimony whereof I have signed this

30 specification.

WILLIAM E. TRUMPLER.
